W. R. CLARK

CURTAIN ADJUSTER

Filed June 17, 1925

INVENTOR:

WILLIAM R. CLARK,

By: Oberde. Kueger,
his Atty.

UNITED STATES PATENT OFFICE.

WILLIAM R. CLARK, OF SAN DIEGO, CALIFORNIA, ASSIGNOR TO W. R. CLARK MANUFACTURING COMPANY, OF SAN DIEGO, CALIFORNIA.

CURTAIN ADJUSTER.

Application filed June 17, 1925. Serial No. 37,661.

This invention relates to devices used for holding curtains properly supported.

One of the objects of this invention is to provide a device by which a curtain can be 5 stretched and evened after being disposed on curtain rods.

Another object is to provide a device by which double curtain-rods can be adjusted by one operation.

Another object is to provide a releasable locking device by which a curtain can be quickly released to such an extent that the rods can easily be removed from the rod-supports.

Other objects will appear from the following description and appended claims as well as from the accompanying drawing, in which—

Fig. 1 is a side elevation of two co-acting curtain-supports of a simple form embodying the invention, one support to be at the upper and the other support to be at the lower end of a curtain.

Fig. 2 is a cross section on line 2—2 of Fig. 1.

Fig. 3 is a fragmentary side elevation of an adjusting screw of a slightly modified form.

Fig. 4 is a fragmentary top plan view of a curtain rod, having knuckle or loop-like termination, to be used on the end of the screw of the type illustrated in Fig. 3.

Fig. 5 is a fragmentary side elevation of an adjusting screw secured in the curtain support, having a knurled nut against which a curtain-rod may abut.

As illustrated, the base members 6 and 7 may be fastened to a wall, or to a window or door-sash, the numeral 8 may indicate portions to which the base members are attached.

The upper member is of plain form and is provided with a front end 9 through which a screw 10 is adjustably disposed.

The screw 10 is provided with an upper reduced portion 11, which fits turnably in curtain-rod-clamps 12.

In this form, two curtain rods are indicated at 13 and 14, and the clamping members 12 are therefore provided with hook-ends 15 at both ends, but it will easily be

understood that, for single curtain rods, the clamping members may be provided with hook at one end only. It is also immaterial whether sheet-metal rods are used as of the 55 form illustrated in the drawing or any other type of curtain-rods, the hook-ends 15 are merely formed to fit over the different and various forms of curtain rods, and the hook-ends, of course, can be slightly modified for 60 different types of curtain rods. Different hook-forms are not illustrated since it is easy to form such hook-ends corresponding to the shapes of curtain rods.

The lower structure varies slightly from 65 the upper, particularly as to the quick-releasing part. The base-member 7 is shorter than the base member 6. A second member 16 is pivotally and shiftably connected with the base member 7. The pin 17 interconnects the two members 7 and 16. The member 7 terminates in a bifurcated end, having the upper extension-end 18 and the lower somewhat longer extension-end 19. The second member 16 has a fork-like termination 20 at one end, and the front termination 9 at the opposite end. The fork-like termination 20 is slotted as indicated at 21, whereby the member 16 may be shifted in relation to the member 7, around the pin 17. 75

In its closest interengagement with the member 7, the member 16 is disposed in the bifurcated end of the member 7 between the extension ends 18 and 19. From this position, the member 16 may be withdrawn until the forked end 20 disengages from the extension-end 18, at which moment the member 16 may be moved or swung around the pin 17 to the position indicated in dotted lines at 22. 80

Considering that a curtain may be placed over and between the curtain-rods 13, as indicated by the heavy dotted lines at 23, and that another curtain may be placed around and between the upper and lower curtain-rods 14 as indicated by the heavy dotted lines 24, it will be clear that both curtains can be released by the simple withdrawal of the member 16 from the bifurcated end of the member 7, since the member 16 would 85 then quickly take the position indicated at 22. 90

100

To place curtains in proper position, the upper curtain-rods are first placed in position, and, while the lower curtain-rods are placed in position, the member 16 is preferably first disengaged preparatory to tightening the curtains. When the curtains and all curtain-rods are in their proper positions in relation to the upper member 6 and the lower member 7, the member 16 is pressed downwardly and then inwardly until the member 16 is properly engaged within the bifurcated end of the member 7. The curtains are by such downwardly swinging and pressing of the member 16 normally tightened to a suitable extent. If, however, further tightening is desired, the upper and lower screws 10 are turned so that the upper and lower curtain-rods are forced apart.

Instead of having small pins 25 provided in the screws 10, the slightly modified screws 26, in Fig. 3, are provided with thumb-wings 27.

Another slightly modified form of a screw is illustrated in Fig. 5, the screw being indicated at 28. This screw is preferably firmly secured in the end 9, while the nut 29 serves to engage by abutment or otherwise the clamping members 12.

If only one curtain rod is desired, the curtain-rod may be provided with a knuckle-like or loop-like termination as indicated at 30, and such a curtain-rod may be slipped over the reduced and shouldered end 11 of the screws 10 and 26 or may abut with the nut 29 by being slipped over the screw 28. This is moreover merely a matter of adapting the invention to the different types of curtain-rods that may be used.

Having thus described my invention, I claim:

1. In a curtain adjuster, brackets for the upper and lower ends of a curtain including sectioned members pivotally and swingably interconnecting sections of the brackets so that the curtain may be tightened by a swinging movement of the bracket-sections in the longitudinal direction of the curtain.

2. In a curtain adjuster, brackets for the upper and lower ends of a curtain including sectioned members swingable in relation to other comparatively stationary members of the brackets so that the curtain may be tightened by a swinging movement of such members and having means whereby the swingable sections may be set against swinging movements in relation to the stationary members to hold the curtain tightened.

3. In a curtain adjuster, brackets for the upper and lower ends of a curtain including sectioned members swingable in relation to other comparatively stationary members of the brackets so that the curtain may be tightened by a swinging movement of such

members and having means whereby the swingable sections may be set against swinging movements in relation to the stationary members to hold the curtain tightened, and adjusting means on the brackets for stretching and evening the tightened curtain. 70

4. In a curtain adjuster, a bracket made of swingably interconnected sections of which one forms a comparatively stationary base, the interconnection between the sections consisting of a pivot and a slotted portion whereby the swingable section can be shifted in relation to the stationary section or base to facilitate a swinging of the one section to the other in a certain shifted 75 position and including means whereby the swingable section can be held on the stationary base against swinging movements, screws turnably disposed through the free ends of the swingable section, and means 80 on the screws for holding curtain-rods.

5. In a curtain adjuster, a bracket having a base by which the bracket may be attached to a wall or the like place and having a bifurcated termination to project 90 from the base, an adjusting member having a portion to engage within said bifurcated end, the bracket and adjusting member having slot and pin interengagement by which the adjusting member may be made to shift 95 back and forth in relation to the bifurcated end and to swing around the pin to be locked in a certain position within the bifurcated end adapted to be released from such locked position by a shifting of the 100 member, and a curtain rod supporting screw disposed in the free end of the adjusting member for screwing movements in the plane of the swinging movements of the adjusting member in relation to the bracket. 105

6. In a curtain adjuster, a bracket made in sections, one of the sections terminating in a bifurcated end and carrying a pivot-pin, the other section having a slotted portion for swingably and shiftably engaging 110 with the pin of the first-named section and adapted to be held in a certain position within the bifurcated end of the first-named section against swinging movements and having rod-carrying and adjusting means 115 on its free end.

7. In a curtain adjuster, a bracket made in sections, one of the sections terminating in a bifurcated end and carrying a pivot-pin, the other section having a portion to fit shiftably in the said bifurcated end and having a slotted portion for swingably and shiftably engaging with the said pin, and rod-carrying and adjusting means in the free end of the bracket movable and adjustable in a direction similar to the plane of the swinging movements of the second-named section. 120

8. In a curtain adjuster, a bracket made in sections swingably interconnected having 125

means by which they may be set and held in a certain relation to one another, a curtain-rod clamp having oppositely disposed jaws to engage over the sides of a curtain-
5 rod, and having perforations transversely to the clamping jaws by which the clamping jaws may be pivotally supported, and sup-

porting and adjusting means for the clamp in the free end of one of the said sections movable in the direction of swinging. 10

In testimony that I claim the foregoing as my invention I have signed my name.

WILLIAM R. CLARK.
